UNITED STATES PATENT OFFICE.

ELMER H. ENGLEHORN, OF DOUGLASTON, NEW YORK.

DESIGN FOR A RAILROAD-CROSSING SIGNAL.

Application filed September 29, 1928. Serial No. 28,324. Term of patent 7 years.

To all whom it may concern:

Be it known that I, ELMER H. ENGLEHORN, residing at Douglaston, county of Queens, and State of New York, a citizen of the United States, have invented a new, original, and ornamental Design for a Railroad-Crossing Signal, of which the following is a specification, reference being had to the accompanying drawing, forming part thereof.

In the drawing Figure 1 is a side view of a railroad crossing signal embodying my design, and, Figure 2, is an end view of this signal.

I claim:

The ornamental design for a railroad crossing signal, as shown.

ELMER H. ENGLEHORN.
